FURNACE

Daniel F. Corcoran, Boston, Mass.

Application September 6, 1941, Serial No. 409,852

2 Claims. (Cl. 126—99)

My invention relates to furnaces, particularly hot air heating furnaces of that class which is constructed with an air-heating radiator through which the products of combustion pass from the heater of the furnace to the chimney, said radiator being provided to augment the heat-radiating surface of the furnace thereby to increase the efficiency of the latter.

My invention has for its object to provide a furnace of the class described with an improved radiator which will be of simple, efficient and inexpensive construction.

To this end I have provided a furnace of the class described equipped with an improved radiator which, in its preferred form, may be constructed and operate as set forth in the following description, the several novel features of the invention being separately pointed out in the claims at the close of the description.

In the accompanying drawings:

Figure 1 is a central vertical sectional view of a furnace constructed in accordance with this invention.

Figure 2 is a section on line 2—2 of Fig. 1.

The illustrated embodiment of my invention comprises a heater that is indicated generally at 10 and, as usual, said heater may be inclosed within a sheet metal casing 11 provided adjacent to its bottom with the usual air inlet (not shown) and at its top with the usual air outlet flues 12 by which the heated air is distributed.

The fire-box 13 of heater 10 supports the usual combustion dome 14 made upon its exterior with a cylindrical nipple 15 surrounding the outlet 16 of the dome. Telescopically fitted upon the nipple 15 is a nipple 17 forming part of the inner wall of a hollow sheet metal lower radiator section or manifold 18 into which the products of combustion are directed from dome 14 by the two nipples 15 and 17.

The lower radiator section 18 is of horseshoe shape, as viewed in plan, and surrounds the heater 10 as shown in Fig. 2, being spaced away from said heater so as to provide an air passage between the two as shown. The dome outlet 16 is connected with the middle of this horseshoe-shaped section 18 and therefore the products of combustion that are discharged into section 18 will, upon entering said section, be divided, part thereof passing through each branch 18a of section 18 to the end of said branch. Each branch 18a is provided at its top and adjacent to its end with an outlet connected by an upwardly extending conduit 19 with the interior of an elongate sheet metal manifold 20 forming part

of an upper radiator section that is indicated generally at 21.

This upper radiator section also includes a second elongate sheet metal manifold 22 that is disposed opposite to and parallel with the manifold 20 with which latter it is connected by an approximately horizontal row of sheet metal pipes or conduits 23a and 23b. Upon the exterior of the outer side of manifold 22 the latter is made with a cylindrical nipple 24 surrounding an outlet 25 provided in said side. This nipple 24 extends through an aperture provided in casing 11 to the exterior of the latter where it is telescopically fitted within a chimney flue 26.

Each conduit 19, Fig. 1, consists in part of a flanged nipple 27 that is an integral part of the lower radiator section 18 and in part of a flanged nipple 28 that is an integral part of the manifold 22 of the upper radiator section, the flanges of said nipples abutting and being fastened together by bolts 29.

The manifold 18 is supported by the nipple 15 of dome 14 and is provided upon its top side and at the middle thereof, with an integral post 30 which serves as a support for the manifold 22 of the upper radiator section 21.

Each branch of the horseshoe-shaped manifold 18 is provided adjacent to its end, and upon the outer side thereof, with an integral tubular clean-out nipple 31 projecting through an aperture formed in the casing 11 to the exterior of the latter, the inner end of said nipple communicating with the interior of manifold 18 and the outer end thereof being normally closed by a plate 32 separably interlocked with supporting hooks 33 projecting from the nipple 31.

The up-draft within the chimney, supplemented by the relatively high temperature of the gases within dome 14 of the heater, causes the products of combustion to discharge from the latter into manifold 18 at the middle thereof, and to proceed thence through both branches of said manifold to and through conduits 19 into manifold 20, and thence through pipes 23a and 23b to manifold 22 from which they are delivered into the chimney flue 26 through nipple 24. Since all of the manifolds, conduits and nipples of the radiator are preferably made from thin sheet metal integrated by welding, or otherwise, they quickly absorb heat from the products of combustion and also quickly transmit said heat to the air within casing 11 which rises to the outlet flues 12. During its upward movement the air within casing 11 passes around all

parts of the radiator and is heated through contact with the latter and also by the heat radiated therefrom. It will be observed from Fig. 2 that the above-described radiator provides a grille-like structure through which the rising air must pass and that the parts of the same are constructed and arranged to provide extensive heat-radiating and heat-transmitting surfaces.

In the preferred form of my invention the manifold 20 is constructed interiorly with a transverse partition 34 thereby dividing the same into two compartments one of which is connected by one of the conduits 19 with one branch of manifold 18 and the other of which is connected with the other branch of said manifold by the other conduit 19. The set of pipes 23a communicate with one of these compartments while the set of pipes 23b communicate with the other compartment. The purpose of this partition 34 is to ensure uniformity, as far as possible, of the flow of the hot gases through the branches 18 and 18a of manifold 18 and the pipes of both sets 23a and 23b.

As shown in Fig. 1 the top walls of the branches 18a of lower section 18 and the pipe conduits of the upper section 21 are inclined upwardly toward their outlet ends thus taking advantage of the tendency of the heated gases to rise to amplify the draft effects.

The radiator structure constructed and arranged as above described is supported mainly by a bail-shaped bracket 35 extending over the top of dome 14 and spot welded at its middle to the latter so that it is an integral part thereof. The opposite ends of this bracket are formed with horizontal lateral extensions 36 which provide seats on which the branches 18a of lower section 18 rest.

What I claim is:

1. The combination with a casing and a heater within said casing having a lateral outlet for the products of combustion, of a radiator comprising a lower section consisting of a manifold hav-

ing an inlet adjacent to its middle that is connected with said heater outlet and also having two branches thereof extending in opposite directions from said inlet around said heater, each branch being made adjacent to its extremity with an outlet, and said radiator also comprising an upper section that is spaced away from said casing and said lower section so that it is surrounded by the air that is within the casing, said upper section consisting of a pair of elongate relatively parallel spaced apart manifolds rigidly connected together by a horizontal row of spaced apart pipe conduits connecting the interiors of said pair and disposed above said heater, one manifold of said pair being made adjacent to its opposite ends with inlets and the other manifold of said pair being made with an outlet adapted to be connected with a chimney, and conduits connecting said inlets with the outlets of said branches.

2. The combination with a heater having a lateral outlet for the products of combustion, of a radiator comprising a lower section consisting of a manifold having an inlet adjacent to its middle that is connected with said heater outlet and also having two branches thereof extending in opposite directions from said inlet around said heater, each branch being made adjacent to its extremity with an outlet, and said radiator also comprising an upper section consisting of a pair of elongate relatively parallel spaced apart manifolds rigidly connected together by an approximately horizontal row of spaced apart pipe conduits connecting the interiors of said pair and disposed above said heater, said pipe conduits being inclined upwardly toward their outlet ends and one manifold of said pair being made adjacent to its opposite ends with inlets and the other manifold of said pair being made with an outlet adapted to be connected with a chimney, and conduits connecting said inlets with the outlets of said branches, the tops of the latter being inclined upwardly toward their outlet ends.

DANIEL F. CORCORAN.
